UNITED STATES PATENT OFFICE.

JOHN B. PRICE, OF WOLLASTON, MASSACHUSETTS, ASSIGNOR TO THE MANHATTAN TYPEWRITER COMPANY, OF NEW JERSEY.

TYPE-WRITING MACHINE.

SPECIFICATION forming part of Letters Patent No. 580,953, dated April 20, 1897.

Application filed November 20, 1896. Serial No. 612,819. (No model.)

To all whom it may concern:

Be it known that I, JOHN B. PRICE, of Wollaston, county of Norfolk, and State of Massachusetts, have invented an Improvement 5 in Type-Writing Machines, of which the following description, in connection with the accompanying drawings, is a specification, like letters on the drawings representing like parts.

10 My invention is embodied in a type-writing machine, and relates especially to the mechanism for supporting and controlling the ink-ribbon, being applicable to machines of the well-known Remington type.

15 The invention consists mainly in a novel construction of the bearing for the ink-ribbon spools and in details of construction of the mechanism for operating the ink-ribbon spools and of the guards below the paper-carriage for supporting the letter-gage and protecting the platen and paper thereon from the ink-ribbon.

Figure 1 is an end elevation of a sufficient portion of a type-writing machine to illustrate a portion of the improvements forming 25 the subject of this invention; Fig. 2, a sectional elevation on the line x^2 of Fig. 1; Fig. 3, an end elevation of one of the hangers or bearings for the shaft of the ink-ribbon spool; 30 Fig. 4, an underneath plan of a portion of the paper-carriage; and Figs. 5 and 6, sectional details thereof on lines x^5 , Fig. 4, and x^6 , Fig. 5, to be referred to.

The general construction and arrangement 35 of the working parts of the machine may be and are shown as substantially the same as in the well-known Remington machines, and do not therefore require to be illustrated or described for an understanding of the present 40 invention.

The ink-ribbon spools a are each connected by a spline with its shaft b , which is supported in bearings formed in lugs A^2 A^3 on the under side of the top frame-plate A of the 45 machine.

In order to securely support the spool-shafts b in their bearings and at the same time permit of their ready detachment therefrom without the use of tools of any kind, the 50 said bearing-lugs A^2 are provided with slotted recesses or notches c of proper size to receive

and support the spool-shaft b without confining the same against lateral displacement.

In order to retain the said shaft in its bearings, it is provided at one end with a collar or 55 enlargement b^2 , fixed thereon, and the bearing-lug A^2 is correspondingly counterbored, as shown, so that when the collar b^2 is seated in said counterbores the shaft is restrained from lateral movement, but is free to rotate in its 60 bearing in the lug A^2 .

The opposite end of the spool-shaft b is extended beyond its corresponding bearing-lug and provided with a head or enlargement b^3 , between which and a collar b^4 , loose on said 65 shaft, is interposed a spring b^5 . The bearing-lug A^3 is counterbored like the one A^2 , and when in working position the spring b^5 tends to retain the collars b^2 b^4 in their corresponding counterbore, and thus retains the spool 70 securely in its bearing. When, however, it is desired to remove the spool or spool-shaft from the machine, it is necessary only to press the end b^3 of the shaft against the stress of the spring b^5 sufficiently to carry the collar b^2 , 75 at the opposite end of the shaft, out from the counterbore, when the said end of the shaft can be removed laterally from its bearing-notch in the lug A^2 , and the other end may then be readily withdrawn from the bearing A^3 . 80

The spring b^5 may be made to press the collars against their bearing-surfaces in the lugs A^2 A^3 sufficiently to afford a slight frictional resistance to the rotation of the spool-shaft and spool, so as to maintain the ink-ribbon in 85 the desired state of tension. The spool-shafts are provided with the usual beveled gears d to enable one or the other of them to be intermittently rotated to advance the ink-ribbon, as the writing proceeds, in the usual manner, one of said gears being engaged by a corresponding beveled gear e on the longitudinal shaft e^2 when it is desired to feed the ink-ribbon in one direction, while the gear on the other spool is engaged by the corresponding 90 beveled gear on said shaft e^2 when it is to feed the ink-ribbon in the opposite direction in the usual manner. The said shaft e is longitudinally movable to engage a gear at one end thereof with that of the corresponding spool-shaft and at the same time disengage the gear at the other end, and it is controlled as 95 100

to its engagement by means of a key f , pivotally supported at f^2 in a lug f^3 , depending from the under surface of the main frame-plate A. Said key is slotted where it engages 5 with its pivot, as shown at f^4 , so that when its notched end is lifted out of engagement with the shaft e^2 said key may be slipped back on its pivot and engaged with its supporting-lug, so as to retain it out of engagement with 10 the said shaft, as shown in dotted lines, Fig. 1.

The shaft e is rotated in the usual manner by means of a beveled gear g , splined thereon and meshing with a beveled gear h , connected with the ratchet-wheel i , loose on the shaft of 15 the spring-actuated carriage-feed disk k . The said ratchet i is rotated in one direction only (namely, the direction of movement of the disk k in feeding the carriage as the writing proceeds) by means of a pawl m , pivoted on 20 said feed-disk and engaging with the teeth of said ratchet i .

In order to prevent reverse rotation of the ratchet i and consequent slackening of the ink-ribbon when the disk k is turned in the 25 opposite direction, as when the carriage is moved back for the beginning of a new line, a retaining-pawl n is provided, engaging with the teeth of said ratchet i and pivotally supported upon a bearing n^2 , projecting from the 30 framework at the rear of the feed-disk k .

The paper-carriage p , a portion only of which is shown, is provided with the usual supports r for the letter-gage t , said supports r having the usual projections or guards r^2 35 for preventing contact between the paper over the platen and the ink-ribbon except at the point struck by the type. Said gage-supports and ink-ribbon guards as heretofore constructed have been adjustably fastened 40 upon lugs u , connected with the paper-carriage, by means of clamping-screws, and much annoyance is frequently caused by the lateral or pivotal movement of said supports r at their point of support, such movement 45 throwing the letter-gage out of proper position. In order to avoid this difficulty, the lugs u are in accordance with the present invention provided with tongues u^2 , which fit

5 closely in and have a long bearing engagement with the sides of slots r^4 in the gage-supports r , (see Figs. 5 and 6,) thus preventing possibility of lateral or angular displacement of the latter.

When it is desired to remove either ink-ribbon spool, the actuating-shaft e must be 5: in such position as to disengage its gear from the gear of the spool-shaft to be removed, and the spool-shaft can then be easily removed from its bearings, as before described.

I claim—

1. In a type-writing machine, the combination of the ink-ribbon spool-shaft having at one end a fixed collar and at the other end a longitudinally-movable spring-pressed collar, with bearing-lugs slotted to admit of lateral 65 insertion and removal of said shaft, and counterbored to receive said collars thereof, substantially as and for the purpose described.

2. The combination of the ink-ribbon spool-shafts, each provided with a beveled gear, of a longitudinally-movable actuating-shaft provided with beveled gears to coöperate with those of the ink-ribbon shafts one at a time, and a pivotally-supported key having its free end notched for engagement with grooves in 75 said driving-shaft, said key being slotted at its point of connection with its pivot whereby said key may be thrown out of engagement with the grooved actuating-shaft and supported by engagement with the frame, substantially as and for the purpose described.

3. The combination of the supporting-arms r for the letter-gage and ink-ribbon guards provided at one end with a parallel walled slot, of the supporting-lugs for said arms provided with a tongue entering said slot to prevent lateral or angular displacement of said arms, substantially as described.

In testimony whereof I have signed my name to this specification in the presence of 90 two subscribing witnesses.

JOHN B. PRICE.
